WINDING MACHINE

George W. Scott, Providence, R. I., assignor to
 Tobe Deutschmann Corporation, Canton, Mass.,
 a corporation of Delaware

Application December 13, 1934, Serial No. 757,350

13 Claims. (Cl. 242—56)

The present invention relates to machinery for automatically making wrappings or rolls of certain types, and more particularly to machinery for making electrical condenser windings.

5 In the prior art, most windings of this nature have been made either wholly by hand operated winding machines in which all of the operations except the winding itself are accomplished by hand, or by machines which in part do some of the operations that the hands otherwise perform.

10 The present invention in particular, deals with a machine for making automatically so called paper condenser windings. In these windings there is usually rolled together a number of layers 15 of paper and a number of layers of tin or aluminum foil in such a manner that the tin or aluminum foil forms opposite electrodes of an electrical condenser. In the ordinary condenser winding there may be first a layer of aluminum foil, next 20 a layer of paper, third another layer of aluminum foil, and on top of this a layer of paper. If it is desired a winding can be made with three layers of aluminum separated by three layers of paper. A number of various types of windings of this 25 nature may be made and with the machine of the present invention, these windings may be made as desired, either large or small, and of the desired electrical capacity and other electrical characteristics.

30 The present invention is particularly designed to overcome the handicap imposed by the flimsiness of the material used. As is well known the paper and foil used in the manufacture of electrical condensers are very fine, and not only do 35 they tear easily if the tension on the sheets is varied, but also it should be noted that because of its delicate nature, it cannot be pushed but must always be drawn. This offers considerable difficulty in designing machinery to handle such 40 material, particularly for the present purpose, since a number of operations must be performed on the material besides merely rolling it on a mandrel.

45 In a machine of the present type where there may be six sheets of foil and paper that go to form the winding, it is necessary to fit individually each one of these six sheets to the point where the mandrel will grasp them and begin to wrap them on a winding element. In addition, after 50 the winding is made, each sheet must be cut at relatively different places so that the connecting foils will not have an opportunity of making electrical contact with each other and thereby create a short circuit between the different layers.

55 After the paper and foil are cut, which is in itself

a difficult task because of their thinness, the winding or roll must be sealed and lastly it must be ejected from the spindle or mandrel. It should also be noted that in order to provide a fully automatic device, the exact number of turns must be wound and following this, after the winding is ejected, the mandrel must come to rest always in relatively the same position to be able to receive the foil and paper.

10 In the present invention condenser windings 10 may be made in relatively large or small sizes. The paper and foil is automatically fed from the individual rolls at the top of the machine. A split mandrel automatically opens and closes to grasp the paper and foil. The foil is rolled with 15 the proper number of turns, the roll is then sealed and finally ejected, whereupon the mandrel returns in position to receive the paper and foil for the making of a new roll. The exact manner in which the mechanism operates, the 20 results obtained, and utility and advantages of the invention, will be better understood from the description given below taken in connection with the drawings showing an embodiment of the 25 invention.

Figure 1 shows a plan view of the invention as viewed from the top.

Figure 2 shows the vertical elevation seen from the front.

Figure 3 shows a side elevation.

Figure 4 shows a fragmentary view in perspective showing in detail the method of feeding the foil and paper, the split mandrel, and the manner in which the foil and paper is received on the 35 mandrel.

Figure 5 shows a fragmentary view in perspective showing in part the cutting mechanism for severing the foil and paper and the cam element for controlling the same.

Figure 6 shows in perspective a detail of a part shown in Figure 5, indicating how the paper and foil are released and fed in the operation of the mechanism.

Figure 7 shows, in perspective, a front view of 45 the machine indicating the various cams and controls of the mechanism.

Figure 8 shows a section taken on the line 8—8 of Figure 1.

Figure 9 is a rear view of the invention looking 50 from the upper part of the device as shown in Figure 1.

Figures 10, 11 and 12 show the details of the spring shuttle for grasping and feeding the foil and paper.

55

Figures 13 and 14 show the rotating position of the mandrel on which the coil is wound.

Figures 15 and 16 show the mandrel as still in an open position.

5 Figures 17 and 18 show the mandrel in position for ejecting the winding.

Figure 19 shows a detail of the clutch mechanism for rotating and releasing the shaft on which the mandrel is mounted.

10 Figure 20 shows a detail of the method of supporting the shuttles indicated in Figure 4, and Figure 21 shows a further detail of the same thing.

In Figures 1, 2 and 3 there is shown a base element 1, upon which is mounted a central casting or frame 2 and a motor 3. The motor 3 is made fast to the frame 1 by bolts 4 or in any other suitable manner. At the extremities of frame 1, there is a second frame 5, which carries a rigid element 6 upon which the rolls 7 of tin foil and paper are mounted. On the frame 2 on which most of the mechanism is mounted, are three upwardly extending brackets 11, 12, and 13, through which run the shaft 14.

25 The shaft 14 is driven indirectly by the motor 3 by means of the sprocket wheel 15. The sprocket wheel drives the sprocket chain 16 which in turn drives the large sprocket wheel 18 carried by the shaft 17 to which a gear train is connected. In this system the gear 18 on the shaft 17 drives the gear 19 through the idler gear 20.

30 On the shaft with the gear 19 is a small gear 21 which drives a larger gear 22 which in turn drives through a further reduction system gear 23 and gear 24. The whole gear system including the gears 18, 19, 20, 21, 22, 23 and 24 being a reduction system to obtain speed for the control shaft 14, driven by the gear 24. The gear system is such that certain gears, principally, the gears 40 18 and 20 may be interchanged with gears of other sizes to vary the operation of the mechanism. This makes it possible within a certain limited range to choose the number of turns that the windings are to have. If the control

45 shaft 14 is made to rotate faster as is the case in providing a lower gear reduction ratio, then the complete operation of the mechanism will take place in relatively fewer turns of the spindle 17 and therefore a condenser of a fewer number 50 of turns will be made. The gearing is shown more in detail in Figure 9, than in Figures 1 and 3. The shaft 14 as has been stated may be called the control shaft. This shaft carries two large cams 25 and 26 as well as a smaller cam 27 as indicated in Figure 3. This shaft also carries a cam 28 and external of the support 10, cams 29, 30, 31 and 32. The cam 28 is shown in perspective in Figure 7 and in section in Figure 8. This cam is made with a flat surface except for a raised 60 portion 33 upon which the finger 34 rides. This finger which is adjustable as indicated by the nut 35, is carried by a lever arm 36 pivoted by the pin 37 in a bridge 38 extending across from the supporting frame 8 to the supporting frame, 65 8. The lever 36 is forked at its upper end to form two prongs 39 extending on either side of the shaft 17. Each prong carries a pin 40 which extends into a groove 41 of a clutch element 42. The purpose of the clutch element 42 is to dis-

70 engage the drive shaft 17 at one end from that at the opposite and carrying the spindle or mandrel 43. This mechanism is shown more clearly in Figures 18 and 19. In Figure 19 it will be seen that the mandrel shaft comprises two parts 75 17 and 17', the shaft 17 being the drive shaft,

driven from the sprocket gear 18'. This shaft carries attached to it, a ring gear 44, whose function will be explained later, and a cone clutch 45 which operates the clutching element 46 to which the shaft 17' is held fast. In the operation of the shaft 14, the raised element 33 on the face of the cam 28 forces the lower end of the lever 36 to the left as viewed in Figure 7 when the part 33 of the cam 28 comes beneath the finger 34 at the lower end of the lever 36. 10 This operation in the view shown in Figure 8 forces the clutch element 46 to the left and as indicated in further detail in Figure 19 brings about the disengagement between the two clutch elements 46 and 45. This would occur very 15 sharply were it not for a cylindrical drag spring 47 which is mounted in the inner face of the clutch cone 45 as indicated by the end of the spring 48. This drag spring is toroid in form and fits in a groove 49 in the clutch element 46. 20 As the finger or roller 34 as shown in Figure 8 is moved to the right, compelling the clutch element 46 to move to the left, a projecting bar 50, carried at the end 39 of the fork element, comes in contact with a roller 51 mounted on the lever arm 52. This lever arm 52 is pivoted in a 25 forked bracket 53 mounted by machine bolts 54 to a part of the frame 55 formed as an extension of the upright bracket 8. The lever arm 52 is pivoted to the forked bracket at 56 and carries 30 at the other end an adjustable stud 57 which is adapted to come in contact with the projecting stud or screw 58 attached to a collar 59 mounted on and made fast to the shaft 17'. Normally 35 a spring 60 between the collar 59 and the collar 61 formed at the outside of the groove 41 of the clutch element forces the clutch element 46 into engagement with the cone 45 projecting into it. In this position the shaft 17' and the shaft 17 are rotated together. As the lever 36 40 through the operation of the cam 28 causes the clutch element 46 to leave the surface of the cone 45, the end projecting piece 50 forces the roller 51 of the lever 52 outward causing the adjustable stud 57 to go in the other direction towards the 45 collar 59. Even after the elements 46 and 45 are disengaged, the element 46 continues to move with weakened force, partly due to the inertia of the system and partly due to the effect of the drag spring 47 furnishing some power to the shaft 17' which continues to move until the projecting stud 58 on the collar 59 comes up against the adjustable pin 57, whereupon the shaft 17' comes abruptly to rest. In this position as will 50 be shown later, the mandrel 43 is opened so that it is ready to receive the sheets of paper and foil 55 preparatory to the next operation. The shaft 14 as has been stated above also carries the cams 25, 26 and 27. The cam 27 is shown in Figures 3, 4, 7 and Figures 13 to 18, inclusive. The cam 60 27 is formed with one large projection 62 as indicated in Figures 13 to 18. This cam is normally rotated in a clockwise position as shown by the arrow A. Above the cam 27 there rides the pin 63 which is at one end of a bell-crank 65 lever 64 mounted on a bracket 65 which is integral with the front bearing 11 of the supporting bracket 18. The lever 64 is pivoted by means of the shaft 66 about which there is wound a spring wire 67 placed against the frame 11 in 70 such a manner to hold the upper end 68 of the lever 64 to the right as shown in Fig. 13. The spring 67 in this position holds the pin 63 against the cam 27. The shaft 17' as has been stated carries the mandrel 43. This mandrel as in- 75

dicated in Figures 13, 15, 16 and 17, comprises a fixed jaw 69 and a pivoted jaw 70. The pivoted jaw 70 is pinned to the back end of the fixture 69 by the pin 71. At the back end of the jaw 70 there is a curved portion 72 which projects upwards from the edge of the fixture as shown clearly in Fig. 17. The arm 68 of the lever 64 is formed at the end in two branches 73 and 74, which are themselves forked as indicated clearly in Figures 13, 15 and 17. The pin 75 extends into this forked element 73 and 74 and carries a collar 76 which fits over the mandrel 43. When therefore the collar 76 is forced over to the right as indicated in Figure 15, the end 72 of the moveable half of the mandrel is forced downward and the movable jaw 70 of the mandrel opens upward in the position shown in Figure 15. When therefore the spring 67 forces the lever arm 68 to swing clockwise as viewed in the position in Figure 15, the mandrel opens to receive the paper and aluminum foil. When, however, the portion 62 of the cam 27 comes beneath the pin 63, the arm 68 swings counterclockwise as viewed from the position shown in Figure 13, and not only does the mandrel close and remain closed, but also the collar moves over the mandrel and in this motion ejects the winding that may be on it. The extreme position indicating this operation is shown in Figures 17 and 18. The two other mentioned cams of the system comprise the cams 25 and 26. The cam 26 controls the mechanism for releasing the tension upon the foil and paper when the shuttle element, about to be explained, is raised, and applying it for drawing the shuttle element downward as viewed from the position shown in Figure 4. The cam 25 controls the cutting of the paper and foil at the proper time as will also be explained shortly. The cam 26 is substantially circular in shape except for a small indentation 77. The roller 78 carried by the arm 79 which forms a part of the hub 80 pivoted concentric with the spindle shaft 17, but not attached to it, controls the movement of the arm 81 which is also formed as a rigid element extending from the hub 80. The arm 81 carries at its end 82 a rigid rod 83 on which are mounted a number of collars 84 fixed by set screws 85 in desired positions. The rigid rod 83 also passes through the center of the collars 86. These collars 86 are at the ends of the levers 87 and are pivoted as indicated in Figures 5 and 6 to the shaft 88 mounted in a bearing bracket 89 attached rigidly to the frame or the base 90. The shaft 88 carries at its free end an arm 91, the lower end of which is provided with a pin 92 which extends to the arm 87 and which carries the rubber roller 93. As indicated in Figure 5, the bracket 89 is formed with a base 94 and a parallel bracket element 95. Between the element 95 and the lower part of 89 there is pivoted a second roller 96 which may butt against the roller 93 because of the pressure of the spring 97. This spring is fastened to the fixed shaft 88 and presses against a piece 98 set between the arm 87 and the arm 91, thus forcing the roller 93 against the roller 96. When the arm, as shown in the position of Figure 5 is moved counter clockwise, the collars 84 come against the collars 86 carried at the lower end of the levers 87 and separate the two rollers. This occurs normally at all times except when the roller at the end of the arm 79 drops into the recess 77 in the cam 26. For this short time the rollers 93 and 96, which may be of rubber or any other suitable friction material, come in contact with one another and are rotated by

means of the spur gears 99 carried at the ends of the rollers 96. These gears are shown in Figures 4 and 5 and act to pull down the shuttle 100 in which the paper and foil is threaded. As indicated in Figure 2, the spur gears 99 are operated by the sprocket chain 101 driven from the sprocket gear 102. This sprocket gear derives its power originally from the gear 44 which meshes with the gear 103 driving the shaft 104. This shaft mounted at the side of the frame 10 is rotated in side bracket bearings 105 and 106. As indicated in Figure 2, there are provided two sprocket chains 101 and 108. 101 as has been explained drives the spur gear 99, while the chain 108 drives the spur gear 111, which in turn drives the entire group of rollers corresponding to the roller 110 driven by the spur gear 111. The driving of the spur gears 99, 112, 113, 114, 115 and 116 operate the pair of rollers to return the shuttle 100 to its lowest position. The spur gears 111, 116, 117, 118, 119 and 120 are driven intermittently as will be explained later. Actually the spur gears 99, 112, 113, 114, 115 and 116 are rotated continuously, but only act to drive the shuttle down when the pair of rollers are forced against one another. This action occurs when the cam 26 occupies a definite position as will be later described. The shaft 104 mentioned above drives continuously the spur gear 102.

As noted in Figure 1 just beyond the bearing 106, there is provided a spring 121 which keeps the sprocket gear 122 out of engagement with the shaft 104, so that the sprocket gear 122 rotates intermittently through the clutch drive 123. This clutch drive is indicated more clearly in perspective in Figure 7 and is operated through the raised portion 124 on the cam 26 by means of the lever arm 125 which is pivoted to a bracket 126 extending from the frame 9. The pivot is seen at 127 in Figure 7. When the arm 125 comes above the raised portion of the cam 26, the clutch 123 is moved to the right as shown in Figure 7 and the shaft 104 in this position drives the sprocket gear 122 as well as the sprocket gear 102 which as has been stated is rotated continuously since it is permanently connected to the shaft 104. The sprocket chain 101 as has been stated, drives the sprocket gear 99, which as is seen in Figure 2 and Figure 4 drives the rubber roller 96. When the lever 87 presses the second roller 93 against the roller 96 through the action of the spring 97 at that instant the shuttle 100 is drawn downward.

There are provided six pairs of rollers 128 and 129, 130 and 131, 132 and 133, 134 and 135, 136 and 137. The spur gear 112 is driven from the spur gear 99 and at a speed lower than the spur gear 99. The spur gears 113 and 114 are driven at the same speed but faster than the spur gear 112. The spur gear 115 is driven slower than 113 and 114 and the gear 116 is driven faster than either 113, 114 or 115. The result is therefore that the shuttles between the rollers 96 and 93 and between the rollers 130 and 131, 132 and 133, 134 and 135, advance more rapidly than those shuttles driven by the rollers 128 and 129, 134 and 135. As the shuttles come down to their end positions all of the shuttles are lined up together, each shuttle having a U shaped opening 138. As indicated in Figure 10, this U shaped opening is made longer in the shuttles that move faster. The shuttles that move faster are the paper shuttles or the shuttles in which the paper is drawn downward and the adjustment of the size of the U shaped opening 138 and the length of the shut- 75

ties are such that the paper extends beyond the edges of the foil. The shuttles are drawn downward at times when the six pairs of rollers mesh together. This occurs when the roller at the end of the lever arm 78 shown in Figure 5 falls in the low part 77 of the cam 26. At this moment the arm 81 carrying the curved rod 83 is released and the spring 87 forces the freely sustained elements against the fixed rollers. While the cam 26 remains in this position, the shuttles are drawn downward. Initially the shuttles are positioned just above the cutting knives 139, 140, 141, 142, 143 and 144 as indicated in Figure 2 and Figure 4. The shuttle 100 comprises two metal strips 145 and 146 which may be joined at one long side but are opened at the top and bottom. The material of the shuttle is preferably made of spring steel and sufficiently flexible so that the sides between which the normal foil or paper is inserted, may be pressed together by the pressure of the springs 87 forcing the rubber rolls against one another. At the top of the shuttle there is provided a flexible strip 147 which is made fixed to the shuttle at one end and to rollers at the other end. This is indicated in Figure 4, where the strip 147 is made fast to the cylinder 110 driven by the spur gear 111. The shuttle is also provided with a small extending hook 109 which comes in contact with a pin 148 extending from the bearing housing 149 through which the roller or cylinder 110 is supported and rotated. It will be noted that the spur gears 116, 117, 118, move at substantially the same speeds, whereas 111 moves faster, 119 slower and 120 faster. This corresponds substantially with the manner in which the shuttles are driven downward and completes the proper cycle for furnishing the paper and foil to the mandrel in such a manner that no foil is exposed. The rollers, returning the shuttles 40 100 as has been stated, are operated intermittently. This occurs when the lever arm 125, as has been stated, comes above the raised surface 124 of the cam 26. In this position all of the rollers 118 are moved and the shuttles drawn upward to 45 the position shown in Figure 4. At this time the rollers 96 and 98 are of course parted, the end 78 of the lever arm 79 being away from the low portion 77 of the cam 26. After the condenser windings have been made as will be explained 50 later, and while the shuttle is in the position shown in Figure 4, the knives 139, 140, 141, 142, 143 and 144 are simultaneously operated. The operation of the knives occurs simultaneously through the action of the plate 150. Each knife 55 is attached and projects into the plate 150. The plate 150 is supported on the shuttle 17' about which it is free to move. The lower end of the plate 150 has extending therefrom an arm 151 at the end of which is a roller bearing 152 which 60 bears against the cam 25. The cam 25 is provided with a projecting raised portion 153 which as shown in Figure 5, throws the arm carrying 152 outward to the right, therefore moving the top of the plate 150 as viewed in Figure 5 to the 65 left. The knives, 139, 140, 141, 142, 143 and 144 are positioned normally as indicated in Figures 2 and 4 with the plate portion facing towards the right and just beyond the slots in the frame 154 where the shuttles pass. The knives are formed 70 of two parts, the cutting plates which have already been named, 139, 140, 141, 142, 143 and 144, and the bearing edges 155 which are held in the frame 154 in a cylindrical perforation in the frame by means of the screws 156. The position 75 of the bearing edge 155 may be properly ad-

justed by rotating or moving the cylindrical body 157 in which the bearing edge is formed. The action of the plate 150 is such as to sweep the knife edge against the bearing just beyond the end of the shuttle.

The knives 139 are set in the plate 150 in the perforations 158 and held in place by the lock bolts 159. These knives may be removed and replaced or sharpened when they become dull. The ejecting mechanism for ejecting the windings when completed has already been explained in connection with Figures 13, 14, 15, 16, 17 and 18. After one winding has been ejected, the mandrel assumes an open position as the pin 63 falls into the recess 160 in the cam 27. This happens immediately upon the ejection of the previous winding. The mandrel is in the position in this case as shown in Figure 4. The next operation is the feeding and the winding of the foil and paper by the downward motion of their respective 20 shuttles 100 to the place where the slots 138 become aligned with the fingers 161 and 162 as indicated in Figure 4. These fingers are pivoted by the shaft 163 held by the frame arm 10. The lower end of the fingers are tensioned by means of 25 a spring 164. The fingers 161, 162 are therefore formed as clamping jaws and it will be noted they are operated from their lower ends through the arms 165 and 166 respectively. Formed as a part of the jaws 161 and 162 from each arm 165 30 and 166, there projects at the end a pin 167 and 168. The movements of the arms are controlled by the cams 29 and 30 moving against the pins 168 and 167 respectively. The cams 29 and 30 as viewed in Figure 4 rotate in a counter- 35 clockwise direction. In Figure 4, the jaws are shown in an open position. When the projection 169 of the cam 30 comes to the right of the pin 167, the projection 170 of the cam 29 is also at the right of the pin 168. The slow movement of 40 the cams 29 and 30 in these positions rapidly force apart from one another the pins 167 and 168 and therefore bring together the jaws or fingers 161 and 162 in a position aligned with the U shaped slot 138 in the shuttles 100. It will be noted in 45 this respect that the projection 169 is convex on top and therefore as the pin 167 rides over it, the pin is actually moved to the right while the pin 168 is moved to the left. Both projections, however, continue to move to the right in the 50 same counterclockwise rotation. These jaws remain closed until the pin or arm 63 of the bell-crank lever 64 rises off the depression 160 in the cam 27 as indicated in a position shown in Figures 13 and 14. When the pin 63 assumes this 55 position the shuttles 100 have already been raised, so that the mandrel when it closes, closes only over the paper and foil held fast by the closed jaws 161 and 162. As the mandrel closes, the jaws 161 and 162 snap open so that the foil and 60 paper is not held below the mandrel when it begins to turn. During this operation, the jaws of the mandrel remain stationary in a position with the opening aligned perpendicularly in the direction of the shuttle. After the mandrel has 65 closed, and the shuttle withdrawn, and also after the jaws 161 and 162 have opened, the clutch mechanism described previously allows the mandrel to be turned by the shaft 17, and the winding of the condenser element begins. This 70 continues until the winding has accumulated the desired number of turns which is adjusted by the proper choice of the gears shown in Figure 9. The choice of gears may be varied since their 75 relative position may be varied by the arm 171 75

carrying the gear 21. The gears 21 and 19 may be mounted in any desired position in the slot 172 depending upon the proper choice of gear size to produce the desired ratio of turns of the mandrel shaft with that of the control mechanism.

As will be clearly understood from the description of the mechanism above, one complete rotation of the cam shaft 14 corresponds to the completion of one winding. The operation of the mechanism is repeated with each rotation of the cam shaft 14. The winding of the condenser foil and paper on the mandrel will continue until the protrusion 173 on the cam 28 comes beneath the finger 34 of the clutch lever 36. When this occurs the shaft 17 driving the mandrel 43 is freed and the winding comes to a stop. When the winding has ceased, the projection 153 on the cam 25 moves the knife plate 150 and the knives as viewed in Figure 2 move to the right cutting off the foil and paper. This is quite a rapid operation and the finger 34 soon passes beyond the projection 173 allowing the shaft 17 to drive again the mandrel shaft 17' and wind up the loose ends of the condenser winding. The mechanism 25 of sealing not previously described then comes into play.

The mechanism is shown in Figure 2, Figure 7 and Figure 8.

Mounted on an extension of the frame 10 is a small glue-pot 174, and above this at the left is mounted a small pulley 175 which is rotatably mounted with a shaft 176 carrying the glue brush 177. That is, the shaft 176 and the brush 177 turn with the pulley 175. A spring is provided 35 at one end of the shaft to keep the brush in the position shown in Figure 2. A line 178 is wound about the pulley 175 to which it is also attached at one end, while the other end is attached to the arm 180. The arm 180 has a projecting finger 40 181, which is held in contact with the cam 32 by means of the spring 182. The arm 180 is pivoted at the base by the pivot 183. The other end of the spring mentioned above is attached to a second arm 184 which also is pivoted with an 45 upwardly projecting finger 185 which is held in position against the cam 31. The projection 186 on the cam 32 throws over the arm 180 to the right, thus raising the glue brush 177 against the condenser winding on the mandrel. Shortly 50 after this occurs, the projection 185 comes in the depression in the cam 31, thus allowing the roller 187 carried at the end of the arm 184 to press against the condenser windings. This completes the sealing operation and shortly after this 55 occurs the finger 34 again comes under the raised portion 33 on the cam 28 bringing the mandrel to rest with the mandrel in a horizontal position, that is the split between the mandrel halves is lined perpendicularly upward in the direction of 60 the center shuttle. The mandrel is brought to a stop in the exact position by means of the mechanism shown more particularly in Figure 19. This is accomplished by means of the stop nut 58 which comes in contact with the head of 65 the set screw 57 as the clutch releases the shaft 17' from the shaft 17. The shaft 17' continues to turn on account of the action of the drag spring until the head of the bolt 58 comes in contact with the projection of the set screw 57. This 70 stops the mandrel in the position above described. The next operation is that of removing the condenser winding and this occurs as is shown in Figures 13 to 18, the winding being completely ejected when the pin 63 has risen to the top of the 75 projection 62 of the cam 27. The pin 63 is im-

mediately returned to the depression 160 and the mandrel is opened in a horizontal position ready to receive the paper and the foil for the new winding. The shuttles 100 in which the paper and foil from the rolls 7 at the top of the frame 6 are threaded normally in the position indicated in Figure 4. At the time that the mandrel is opened the rollers 96 and 98, shown more clearly in Figure 6 and the other corresponding rollers are brought together by means of the roller 18 at the end of the arm 19 dropping into the recess 11 in the cam 26. This brings downward the shuttles in their proper speeds and to the position where the jaws 161 and 162 may grasp all of the foil and paper by coming together in the U shaped opening of the shuttle slots. The rolls 96 and 98 are immediately released when the shuttles have reached their lower position and as soon as the jaws 161 and 162 have grasped the paper and foil, the rollers 110 are operated carrying upwards or returning the shuttles 100 to the position indicated in Fig. 4. The mandrel is then closed by the pin 63 rising out of the depression 160. The jaws 161, 162, following this are opened and then the shafts 17 and 17' are again connected so that the mandrel is rotated for winding up the next winding. The machine is capable of producing condenser windings of a size depending upon the width of the paper and foil that the machine normally carries. The number of turns may be determined solely by the proper choice of gears as has been explained above and condenser windings of from 50 to 60 turns have been made in the present type of machine herein described. These condenser windings may be rapidly made and the machine of the present invention is capable of turning out from at least 3,000 to 10,000 such windings per normal day.

Without further enumerating the variations that the present embodiment might take, and without limitation to the exact embodiment described above, I now claim as my invention:

1. In a machine for automatically making condenser windings, means for feeding the paper and foil including shuttle means formed of spring metal in which paper and foil are advanced, a mandrel, clamping means positioned below said mandrel and in line with said shuttle for grasping the paper and foil in said shuttle, said mandrel being split and means for opening and closing the same to hold and turn said paper and foil.
2. In a machine for making automatically condenser windings, a drive shaft, a mandrel shaft including a mandrel and means for coupling said shafts together, including means providing a weaker friction drive as the shafts become uncoupled and means operated thereafter to bring the mandrel shaft to rest in a desired position.
3. In a machine for making automatically condenser windings, a mandrel shaft having a mandrel formed of two parts, one pivoted adjacent the other, and having a projecting end, a collar positioned over said mandrel, and means including a cam for moving said collar in positions at the free end of the mandrel, at the end having the projection, and in a position between.
4. In a machine for making automatically condenser windings, means for winding automatically paper and foil on a mandrel, means for stopping said mandrel for cutting the foil and paper, means for continuing the winding to wind the cut ends, means for sealing the same and means for stopping the mandrel when the sealing is completed.

5. In a machine for making automatically condenser windings, means for winding automatically paper and foil on a mandrel, means for stopping said mandrel for cutting the foil and paper, means for continuing the winding to wind the cut ends, means for sealing the same, means for stopping the mandrel when the sealing is complete and means for ejecting the winding and threading the new winding while said mandrel is at rest.
10. In a machine for making automatically condenser windings, a frame, means for supporting a plurality of paper rolls on said frame, a plurality of guides, each of said guides being provided with a shuttle, means including said shuttles for feeding the material from said rolls to a central point, a mandrel positioned at said central point and means positioned below the mandrel for grasping the material in said shuttles and means for returning said shuttles to a normal position.
15. In a machine for making automatically condenser windings, a frame, means for mounting rolls of foil and paper at points near the top of said frame, means for threading said foil and paper to a central point including a plurality of shuttles substantially enclosing said paper and foil, guiding means for guiding said shuttles, means for suspending said shuttles normally in the upper part of said guiding means, a plurality 25 of knives positioned at various points below the normal position of the shuttles, means for operating said shuttles to bring them together at a central point, a mandrel positioned at said central point and means for grasping the paper and foil in said shuttles and means allowing said shuttles to return to their normal position.
20. In a machine for making automatically condenser windings, a frame, means for mounting rolls of foil and paper at points near the top of said frame, means for threading said foil and paper to a central point including a plurality of guides, a spring shuttle provided in each of said guides substantially surrounding said foil and paper, means for exerting pressure on the outside of said shuttle to grasp said foil and paper and to advance simultaneously said shuttles to a central position, means provided at the central position for grasping the paper and foil in said shuttles and means for returning the shuttles to their 30 normal position.
25. In a machine for making automatically condenser windings, a shuttle mechanism for feeding the foil and paper comprising a guide having a shuttle therein comprising two spring surfaces at each side of said paper and means providing an opening at the lower part of said shuttle for grasping the paper and foil within the 35
10. In a machine for automatically making condenser windings, a frame having spindles for holding rolls of foil and paper spaced substantially radially from a central assembly point, a plurality of guides, means for drawing the foil and paper through the guides to the mandrel means, means for retracting the drawing means, means for grasping the ends of the foil and paper, and mandrel means for winding the same.
15. In a machine for automatically making condenser windings, in combination means for feeding foil and paper of a plurality of rolls of the same to a central point, a mandrel positioned at said central point, said mandrel having one 20 stationary part and one pivoted part, the pivoted part having a portion adapted to fold with the stationary part and an extending arm at the other end thereof, a collar positioned over said mandrel substantially at the point of pivot, means 25 for moving said collar longitudinally of said mandrel whereby the winding is ejected when the collar is moved in one direction and the mandrel is opened when the collar is moved in the other direction.
20. In a machine for automatically making condenser windings in combination means for feeding a plurality of rolls of foil and paper to a central point, said means comprising a frame having a plurality of guiding members, means 30 for moving said foil in said guiding members and a plurality of cutting edges each positioned in said frame at correspondingly different points in said guiding means corresponding to different distances from said central point and means singly 35 operative for operating said several cutting means for severing said foil and paper.
25. In a machine for automatically making condenser windings in combination, a frame having a plurality of substantial radial guides for 40 guiding strips of foil and paper to a central point, a pair of cutting knives positioned across said guides, means holding one set of said knives in a fixed position and means operative to move the other set of said knives to sever said foil and 45 paper.
